CLAIM

The ornamental design for front bezel for a computer enclosure, as shown and described.

DESCRIPTION

FIG. 1 is a perspective view of a front bezel for a computer enclosure showing my design;

FIG. 2 is a front elevational view thereof;

FIG. 3 is a left side, elevational view thereof;

FIG. 4 is a right side, elevational view thereof;

FIG. 5 is a top plan view thereof; and,

FIG. 6 is a bottom plan view thereof.

Broken lines shown in the drawings illustrate features of the front bezel that form no part of the claimed design.
